(57) **CLAIM**

The ornamental design for a hammock stand, as shown.

DESCRIPTION

FIG. 1 is a front elevational view of a hammock stand showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view thereof; and,

FIG. 8 is another front perspective view thereof, shown with a hammock.

The broken line showing of a hammock illustrates environmental subject matter and forms no part of the claimed design.

The claimed hammock stand is used to hang a hammock.
